UNITED STATES PATENT OFFICE.

HUGO LUYKEN, OF BIELEFELD, GERMANY, ASSIGNOR TO THE FIRM: DÜRKOPP-
WERKE A. G., OF BIELEFELD, GERMANY.

CHARGING DEVICE FOR SHAFT FURNACES.

Application filed March 8, 1924. Serial No. 697,927.

To all whom it may concern:

Be it known that I, HUGO LUYKEN, a German citizen, and residing at Bielefeld, Germany, have invented certain new and useful 5 Improvements in Charging Devices for Shaft Furnaces, of which the following is a specification.

When charging shaft-furnaces over an inclined chute terminating in the shaft of the 10 latter, usually, the drawback occurs that the coarse portion of the charge separates from the fine portion of the same, so that the distribution of the charge in the shaft of the furnace becomes non-uniform and results 15 in an irregular burning and draught therein and thus in a reduced capacity of the furnace.

The present invention provides improved means by which this drawback is effectively 20 overcome.

The accompanying drawing represents the improved arrangement in a sectional side elevation.

The furnace *a* has at the top end of its 25 shaft *b* an inclined charging chute *c* in a way known in the art.

According to the present invention, said chute *c* extends somewhat into the shaft by means of a removable piece *d*, while the 30 latter is protected against the ascending heat and flame in the shaft by means of a guard *e* which extends from said piece in rectangular downward direction and which preferably terminates in the furnace shaft 35 wall. Underneath said chute extension piece *d* and on the opposite side of the inner furnace wall, a downwardly inclined baffle-

plate *f* is provided on the latter, which, like the chute extension piece *d*, has a guard *g* extending therefrom in rectangular downward direction and preferably terminating in the furnace shaft wall. 40

By these means, the fuel distribution in the furnace shaft becomes almost perfect and the capacity of the furnace is thereby 45 considerably increased—according to experiments actually made, up to 25% and more.

What I claim, is:

1. In combination, a shaft of a shaft- 50 furnace, an inclined charging chute at the top end of said shaft, a removable extension piece on said chute projecting somewhat into said shaft, and a downwardly inclined baffle-plate located underneath said chute 55 extension piece and on the opposite side of said shaft, substantially as and for the purpose set forth.

2. In an arrangement as specified in 60 claim 1, a guard against heat and flame provided both on said chute extension piece and on said baffle-plate and extending therefrom in rectangular downward direction and terminating in the wall of said shaft, substantially as and for the purpose 65 set forth.

In testimony whereof I have hereunto set my hand in the presence of two subscribing witnesses.

HUGO LUYKEN.
